ROTARY CRUSHER

Frank W. Hack, Des Plaines, Ill.

Application March 9, 1949, Serial No. 80,451

15 Claims. (Cl. 241—252)

1

This invention relates to improvements in crushers such as are used for crushing or breaking rock, ore and other materials.

More particularly this invention relates to a crusher having rotating anvil members.

Heretofore, crushers have been used in which a rotating anvil is operated against a stationary anvil for breaking lumps therebetween. Such a construction necessarily produced considerable friction at the contact surfaces of the anvil and excessive wearing of the parts resulted.

According to the teachings of the present invention a pair of anvils having generally circular faces are disposed opposite each other in a tubular housing. One anvil, hereinafter referred to as the drive anvil, has a working face that is inclined relative to the central axis of the housing about which it is rotated by gearing located outside of the housing. A driven anvil is spring pressed against the drive anvil, being secured in an anvil head which is free to reciprocate in the tubular housing. While the face of the driven anvil is disposed at an angle to the central axis of the housing, it is perpendicular to an oblique axis about which it may freely rotate. When the drive anvil is rotated it will move with the well known wobble-plate camming action, first forcing the driven anvil longitudinally in the housing against the compression of the springs and then permitting the springs to return it to its original position. Since the drive anvil rotates from 300 to 500 revolutions per minute, a crushing action, in the nature of a trip hammer movement, is directed against the rock or ore fed in between the anvils.

Wear due to friction between the moving parts of the anvils is substantially eliminated by the freely rotatable mounting provided for the driven anvil. This construction permits a rolling and grinding action to take place between the contacting surfaces, which action has the added advantageous effect of grinding the small pieces of rock between the surfaces to a substantially granular consistency.

It is therefore an object of this invention to provide a rotary crushing machine in which wear due to friction between the contacting surfaces of the anvil is largely eliminated.

Another object of this invention is to provide a crushing machine in which both crushing and grinding actions are utilized to reduce ore to a granular form.

A further object of this invention is to provide a rotary crusher in which anti-friction bearings are employed to absorb the crushing

2

impact, permitting controlled rotation of the driven anvil in the reciprocating anvil head.

A still further object of this invention is to provide a rotary crusher in which the drive anvil rotates the driven anvil and operates with a camming action to cause reciprocation of the driven anvil.

Another object of this invention is to provide a crushing machine having a generally tubular housing construction which may be made from standard piping.

Another and further object of this invention is to provide a crushing machine in which wearing parts may be quickly replaced without dismantling the machine.

Another and still further object of this invention is to provide a crusher having means for adjusting the pressure exerted between the anvil faces to accommodate the pressure requirements for crushing various materials.

Other objects, features and advantages of the present invention will be apparent to one skilled in the art from the following detail description, taken in connection with the accompanying drawings.

On the drawings:

Figure 1 is a fragmentary elevational view, partly broken away and partly in section, of the rotary crusher of the present invention;

Figure 2 is a vertical sectional view taken substantially on line II—II of Figure 1;

Figure 3 is a fragmentary vertical sectional view taken substantially on line III—III of Figure 2;

Figure 4 is a fragmentary vertical sectional view taken substantially on line IV—IV of Figure 1;

Figure 5 is a fragmentary plan view of the crushing machine of the present invention;

Figure 6 is an elevational view of the anvils of the present invention, isolated from the rest of the crushing machine, showing the anvil faces at the beginning of the crushing stroke;

Figure 7 is an elevational view of the anvil members similar to Figure 6 but showing the position of the anvils at an intermediate portion of the stroke; and

Figure 8 is a view similar to Figures 6 and 7 showing the anvils in their relative positions at the end of the crushing stroke.

As shown on the drawings:

In Figure 1, the reference numeral 10 indicates generally the housing of a rotary crushing machine. This housing comprises a tubular body member 11 which has an end portion 11a of

reduced external diameter closely disposed in a circular opening 12a of an upstanding end plate 12, with a shoulder 11b abutting the plate 12. The end portion 11a is bottomed in a cylindrical recess 16a located in a flange 16 of a spring cover member 15. The cover member 15 also includes a cylindrical body portion 17 on which is threaded a cap member 18.

At its opposite end, Figure 3, the body member 11 has an end portion 11c of reduced external diameter extending through an opening 20a of an upstanding end plate 20 and has a shoulder 11d abutting the plate 20. The end portion 11c is bottomed in a cylindrical recess 22a of an end cover member 22. The body member 11 is held in place between the end plates 12 and 20 by a plurality of bolts 24, the heads of which are disposed against the flange portion 22b of the cover member 22 with nuts 25 threaded onto their opposite ends against the flange 16 of the cover member 15.

As best seen in Fig. 1 the end plates 12 and 20 extend below the body 11 and have substantially horizontal foot members 12b and flanges 12c arranged to provide a supporting base for the crusher.

To afford means for introducing rock and ore into the crushing machine, an opening 11e, Figures 2 and 3, is provided in the upper surface of the housing 11. A chute 27, having diverging front and rear walls 28 and 29, respectively, is secured over the opening 11e by a plurality of cap screws 30. The side walls 31 and 32 of the chute are disposed on the housing 11 close to the edge of the opening 11e.

Diametrically opposed to the inlet opening 11e in the housing 11 is a discharge opening 11f arranged to receive a replaceable ore chamber unit, which will be described in detail hereinafter.

Disposed inside the housing 11 immediately below the inlet opening 11e, is a drive anvil 35 which has a flat circular working face 35a of hardened steel surrounded by an inclined annular peripheral portion 35b. The plane of the face 35a of the anvil is inclined at an angle other than a right angle to the central axis of the tubular housing 11 as shown in Fig. 3. The anvil is arranged to rotate with a revolving head 36 which has a projection 36a threaded into the back of the anvil. The head 36 is secured to a drive shaft 38 by a lock nut 39, the drive shaft being disposed for rotation on the central axis of the tubular housing by means of a flywheel 41 and a driven gear 42 which is associated with an external source of power.

A set of roller thrust bearings 45 is disposed between the end cover 20 and the head 36. To prevent dust from the crushing operation from finding its way into the bearing 45, a seal ring 46 is held by a retainer 47 tightly against the head 36 and also against the inner wall of the housing 11. The drive shaft itself rotates on the central axis of the tubular housing 11 and is journaled in anti-friction bearings 48 in a tubular housing 49 welded to the end plate 22. Thus, the anvil 35 is disposed for rotation about the central axis of the tubular housing but, due to the inclined position of the anvil, its face will constantly change its angular position relative to a plane perpendicular to the axis of rotation of the housing.

A driven anvil 50 is disposed beneath the inlet opening 11e in confronting relation to the drive anvil 35. The driven anvil has a circular face 50a bounded by an annular inclined peripheral

portion 50b, which, in the embodiment illustrated in Figure 3, is slightly narrower than the annular portion 35b of the anvil 35. An anvil head 52 of circular vertical cross-section is disposed in the tubular housing 11 behind the anvil 50, having its surfaces slightly spaced from the wall of the housing. A cylindrical bore 52a is provided in the head 52 disposed at an angle downwardly from the central axis of the housing 11. An idler shaft 54 is journaled for rotation in a double roller bearing assembly 55, the races of which are pressed between the shaft 54 and the walls of the inclined cylindrical bore 52a abutting a shoulder 52b of the head 52.

An enlarged circular end portion 54a of the shaft 54 is threaded into the anvil 50 so that the anvil is free to rotate with the shaft.

To absorb the shock loads incident to the operation of the crusher, a roller thrust bearing assembly 56 is arranged between the end portion 54a of the shaft 54 and a shoulder portion 52c of the anvil head 52. One race of the bearing 56 is positioned in a recess 54c in the end portion of the shaft 54, while the other race is pressed against the shoulder 52c. A nut 57 threaded on the shaft 54 draws the end portion 54a against the bearing assembly 56 and urges the bearing assembly 56 into place against the shoulder 52b. The shaft 54 is thus mounted for free rotation on the roller bearings 55 and 56. Since the thrust load will be borne by the thrust bearing 56, no binding of the shaft will result during operation.

The dust generated in the crushing operation is excluded from the bearings 55 and 56 by means of a resilient seal ring 58 which is held in a retainer 59 against a shoulder of the anvil head 52 and against the rotating anvil 50.

As best seen in Figures 1 and 3, a plurality of reciprocating shafts 60 are threaded into a plate 61 which is secured by screws 62 to the anvil head 52. Near one end, each shaft 60 is slidably disposed in a hollow adjusting member or sleeve 64 which has a forward shoulder 64a, a rear hexagonal head 64b and a central exteriorly threaded portion 64c which is threaded into an opening 16b in the end cover member 18. A coil spring 63 is disposed around each shaft 60 between the shoulder 64a and a thrust washer 65, Figure 3, near the forward end of the shaft 60. Since the longitudinal backward movement of the anvil head 52 causes the springs 63 to be compressed, it will be readily seen that the force which resists movement of the anvil and therefore the reaction force causing forward movement thereof can be varied by adjusting the sleeve 64 in the end cover 18.

The head 52 is mounted for reciprocating movement in the housing 11 but held against rotation therein by means of blocks 66, Figures 1 and 4, which are secured by cap screws 67 in recesses 52d extending longitudinally on both sides of the head 52. Each block 66 extends outwardly through a longitudinal slot 68 in the housing 11 and has a V-shaped outer contact portion 66a arranged for sliding movement in a V-shaped surface of a gib 70. The gib 70 has a reduced portion 70a fitting tightly into a slot 72a of a support block 72 which is held in a substantially horizontal position by braces 73 attached to the housing 11. A plurality of screws 74 secure the gib 70 to the support block 72. To prevent dirt from entering the housing, a felt seal 75 is arranged in a groove 76 in the housing on all four sides of each slot 68 in the housing. The seal 75 is held in place by washers 77 and a cover

member 78 secured to the housing by cap screws 79.

The anvil head 52 is thus mounted for reciprocating movement in the housing on the gib 70 but is prevented from rotating therein.

In Figures 3, 6, 7 and 8, the anvils are shown in various operating positions. In Figures 3 and 6, the anvil 35 has forced the anvil 50 as far as it can go toward the left against the compression of the spring 63. Figure 8 shows the anvils when the spring has returned the anvil 52 to the right. Figure 7 illustrates an intermediate position. It is to be noted that the drive anvil 35 does not move longitudinally in the housing but only rotates while the anvil 50 rotates and reciprocates.

At the beginning of the stroke, as illustrated in Figure 8, the flat faces of the anvils are in contact, while at the middle of the stroke, Figure 6, only the peripheral edges of the anvil are in contact. Thus, it will be seen, that between these two extremes the contact of the faces is decreased while the contact of the peripheral portions is increased.

In operation, rock will be fed in between the anvils when they are in the position illustrated in Figures 3 and 6. As the drive anvil 35 is further rotated, the springs 63 move the anvil 50 toward the anvil 35 as the anvils approach the position shown in Figure 8. Thus, the rock will be squeezed between the anvils. Since the anvil 35 rotates at a speed of from 300 to 500 R. P. M., the anvil 50 will be reciprocated rapidly in the housing and the rock will be subjected to a series of rapid hammer-like blows, as the larger pieces are broken and give way between the anvils.

As previously stated, the rolling action of one anvil on the other tends to grind the smaller pieces of rock to a granular consistency.

To receive the crushed ore and rock after it has been broken between the anvils, there is positioned in the discharge opening 11f of the housing 11 an ore chamber unit 80. This unit 80 comprises two longitudinal side members 81 and 82 which are secured at their end portions to plates 83 and 84 by a plurality of cap screws 85. As best seen in Figure 2, the side members 81 and 82 are slanted downwardly and inwardly to direct the crushed ore into a processing unit 86 positioned therebelow. A side plate 87 is secured between the casing of the unit 86 and the housing 11 of the crushing machine immediately behind each side member.

Each of the end plates 83 and 84 has an upper surface formed on the radius of the inner surface of the housing 11 and is provided on this surface with a series of spaced, radially extending, squared slots 83a. A set of square bars 88 is supported across the chamber with their ends positioned in the slots 83 of each end plate. The spacing of the bars permits a rough grading of the crushed particles of ore, and, since the bars are square and radially disposed, a tapered discharge passage is formed between the bars which prevents clogging.

The ore chamber 80 is mounted as a unit in the discharge opening by a plurality of bolts 89 and 90, Figure 3. The bolts 89 have their heads countersunk in the end plate 20 and pass freely through a spacer block 91 for threading into the end member 84 of the unit. The bolts 90 secure the end member 83 to an upright support member 92 which has a substantially horizontal cradle member 92a, Figure 1, disposed in supporting contact under the body 11. Thus, by removal of the bolts 89 and 90 the chamber 80 can

be quickly and easily replaced when worn. Also, the bars 88 are easily removed from the unit itself when it is disconnected from the housing.

It is now seen that there is provided in this invention, a drive anvil having an inclined face mounted for rotation about the central axis of the tubular housing. A driven anvil, freely rotatable about an inclined axis, is arranged to reciprocate in the tubular housing in cooperation with a slidably spring-pressed anvil head and to transmit the crushing load through anti-friction thrust bearing to the anvil head. The angle between the faces 35a and 50a is indicated to be substantially the same as the angle between the axes of the shafts 38 and 54. This relationship insures the contacting or parallel relationship between said faces that is illustrated in Fig. 8. The axes of said shafts 38 and 54 lie in the same plane and therefore are intersecting. The peripheries of the anvil faces 35a and 50a lie in a cylinder having substantially a common axis.

The anvils rotate at such a speed as to cause hammer-like blows to be struck on the rock disposed therebetween and to discharge the crushed rock into a replaceable ore chamber.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a crushing machine, a pair of anvils mounted for rotation about axes lying in the same plane and inclined toward each other, said anvils presenting fully confronting circular working faces the outer peripheries of which lie in cylinders having substantially a common axis, the face of one of said anvils being inclined at an angle other than 90° to its anvil axis and the face of the other anvil being at 90° to its anvil axis, means resiliently urging said working faces toward each other and driving means for rotating one of said anvils.

2. In a crushing machine, a pair of anvils having axes inclined toward each other and intersecting each other if projected, a first of said anvils being mounted for rotation in an axially fixed position and having a working face which lies substantially in a plane inclined at other than 90° to said first anvil axis, the second of said anvils being mounted for free rotation about its axis and for bodily movement toward and away from said first anvil and having a working face which lies substantially in a plane at right angles to said second anvil axis, means constantly and resiliently urging said second anvil toward said first anvil, and driving means for rotating said first anvil, the inclinations referred to being such that as said anvils are rotated their respective working faces tend under the action of said resilient means to move relatively toward each other from an open relationship with marginal portions only in contact to a substantially full face contact.

3. In a crushing machine, a housing having a cylindrical inner surface, a pair of anvils mounted in said housing having axes inclined toward each other and intersecting each other if projected, a first of said anvils being mounted for rotation in an axially fixed position and having a circular working face which lies substantially in a plane inclined at other than 90° to said first anvil axis, the second of said anvils being mounted for free

rotation about its axis and for bodily movement toward and away from said first anvil and having a circular working face which lies substantially in a plane at right angles to said second anvil axis, said anvils being of slightly less diameter than said cylindrical surface to provide running clearance with said housing, means constantly and resiliently urging said second anvil toward said first anvil, and driving means for rotating said first anvil, the inclination referred to being such that as said anvils are rotated their respective working faces tend under the action of said resilient means to move relatively toward each other from an open relationship with marginal portions only in contact to a substantially full face contact.

4. In a crushing machine, a tubular housing, a first anvil mounted therein for rotation about the axis of said housing and having a circular central working surface which is flat and lies in a plane inclined to said axis at other than 90°, a second anvil mounted for longitudinal movement in said housing, said second anvil being mounted for rotation about an axis inclined to said housing axis and having a circular central working surface which is flat and lies in a plane at right angles to the second anvil axis, said anvils having a small circumferential clearance with respect to said housing, means for driving said first anvil and resilient means urging said second anvil toward said first anvil.

5. In a crushing machine, a tubular housing, a first anvil mounted therein for rotation about the axis of said housing and having a circular central working surface which is flat and lies in a plane inclined to said axis at other than 90°, a second anvil mounted for longitudinal movement in said housing, said second anvil being mounted for rotation about an axis inclined to said housing axis and having a circular central working surface which is flat and lies in a plane at right angles to the second anvil axis, said anvils having a small circumferential clearance with respect to said housing and said working faces having beveled marginal surfaces normally in contact with each other at some point during rotation of said first anvil, means for driving said first anvil and resilient means urging said second anvil toward said first anvil.

6. In a crushing machine, a first anvil mounted for rotation about its axis and having a working face fixedly disposed at an angle other than a right angle to said axis, a second anvil having an axis of rotation lying in the same plane as said first axis but at an angle thereto substantially equal to said first mentioned angle and having a working face fixedly disposed at right angles to said second anvil axis and opposed to said first working face, means constantly and resiliently urging said working faces toward each other and power means driving only one of said anvils to effect positive rotation of said one anvil, the other anvil being freely rotatable and driven from said one anvil partly through direct frictional contact of said working faces and partly through indirect frictional contact through the material undergoing crushing action.

7. In a crushing machine, a first anvil mounted for rotation about its axis and having a working face fixedly disposed at an angle other than a right angle to said axis, a second anvil having an axis of rotation lying in the same plane as said first axis but at an angle thereto substantially equal to said first mentioned angle and having a working face fixedly disposed at right angles to

said second anvil axis and opposed to said first working face, means constantly and resiliently urging said working faces toward each other and power means driving only one of said anvils to effect positive rotation of said one anvil, the other anvil being freely rotatable and driven from said one anvil partly through direct frictional contact of said working faces and partly through indirect frictional contact through the material undergoing crushing action, said working faces having cooperating central circular flat portions and beveled peripheral portions that exert a crushing, rolling and grinding action upon such material.

8. In a crushing machine, a housing having an inner cylindrical surface, a drive anvil within said housing mounted for rotation about the axis of said cylindrical surface and having a working face disposed at an angle other than a right angle to said axis, a driven anvil within said housing mounted for rotation about an axis lying at an angle to said first axis substantially equal to said first mentioned angle and having a working face disposed at right angles to said driven anvil axis, said working faces being opposed to each other and having peripheral running clearance with respect to said cylindrical surface, means constantly and resiliently urging said working faces toward each other and power means driving said drive anvil.

9. In a crushing machine, a housing having an inner cylindrical surface, a drive anvil within said housing mounted for rotation about the axis of said cylindrical surface and having a working face disposed at an angle other than a right angle to said surface, a driven anvil within said housing mounted for rotation about an axis lying at an angle to said first axis substantially equal to said first mentioned angle and having a working face disposed at right angles to said driven anvil axis, said working faces being opposed to each other and having peripheral running clearance with respect to said cylindrical surface, means constantly and resiliently urging said working faces toward each other and power means driving said drive anvil, said working faces having cooperating central circular flat portions and beveled peripheral portions that exert a crushing, rolling and grinding action upon such material as is disposed therebetween to be crushed.

10. A crushing machine, comprising a housing having an upper feed opening, a lower discharge opening and an inner cylindrical surface with a horizontal axis, a drive anvil within said housing mounted in axially fixed position for rotation about said axis and having a working face at an angle other than a right angle to said axis, a driven anvil within said housing mounted for axial movement therein and freely rotatable about an axis inclined at an angle to said first axis substantially equal to said first mentioned angle, said driven anvil having a working face at right angles to said driven anvil axis and confronting said first working face, said anvils having peripheral running clearance with respect to said cylindrical surface and having an angular relationship at one stage during the operation of said machine that provides an opening therebetween beneath said feed opening and cooperating therewith for receiving material to be crushed, means constantly and resiliently urging said driven anvil axially of said housing toward said drive anvil, and power means driving only said drive anvil.

11. A crushing machine, comprising a hous-

ing having an upper feed opening, a lower discharge opening and an inner cylindrical surface with a horizontal axis, a drive anvil within said housing mounted in axially fixed position for rotation about said axis and having a working face at an angle other than a right angle to said axis, a driven anvil within said housing mounted for axial movement therein and freely rotatable about an axis inclined at an angle to said first axis substantially equal to said first mentioned angle, said driven anvil having a working face at right angles to said driven anvil axis and confronting said first working face, said anvils having peripheral running clearance with respect to said cylindrical surface and having an angular relationship at one stage during the operation of said machine that provides an opening therebetween beneath said feed opening and cooperating therewith for receiving material to be crushed, means constantly and resiliently urging said driven anvil axially of said housing toward said drive anvil, power means driving only said drive anvil, and anti-friction bearings supporting each of said anvils for rotation and against thrust loads.

12. A machine for crushing rock or the like comprising a tubular housing, a first anvil rotatably mounted in said housing about an axis common to the axis of said housing and having a rock contacting face inclined relative to said axis, a second anvil mounted in said housing for free rotation about an oblique axis and having a rock contacting face normal to said oblique axis, an anvil head associated with said second anvil and movable longitudinally of said housing, spring means between said housing and said anvil head, means for adjusting the tension of said spring means, and means for rotating said first anvil, said spring means tending to urge the rock crushing faces of said anvils into contact with each other, whereby rotation of said first anvil causes rotation and reciprocation of said second anvil.

13. A machine for crushing rock or the like comprising a tubular housing, a power driven rotary anvil in said housing having a face inclined relative to the axis of rotation of the anvil, a second anvil movable longitudinally in said housing and freely rotatable about an axis inclined relative to the axis of rotation of said power driven anvil, said anvils having peripheral running clearance with said housing, the face of said second anvil being substantially normal to its axis of rotation and in full confronting relationship to the inclined face of said power driven anvil, and spring means urging the faces of said anvils together, whereby said power driven anvil moves said second anvil longitudinally in said housing during a portion of each revolution of said power driven anvil against the action of said spring means.

14. A machine for crushing rock or the like

comprising a tubular housing, a pair of oppositely disposed anvils mounted for rotation in said housing with running clearance between said anvils and said housing, said anvils having flat working faces fully confronting each other and defining a rock-crushing zone therebetween, one of said anvils being rotatable about the axis of said housing and having a face inclined at other than 90° to the axis, the other anvil being slideable in said housing and rotatable about an axis inclined to said first axis and having a face normal to said other anvil axis, and spring means urging said anvils together, the faces of said anvils in an open position being in contact at their rim portions during a portion of each rotation of said one anvil and being in closed flat contact across their faces during another portion of each rotation, said spring means tending to move said slideable anvil longitudinally in said housing in one direction to close said anvils and said inclined anvil during rotation tending to move said slideable anvil in an opposite direction toward an open position.

15. A machine for crushing rock or the like comprising a tubular housing, a pair of opposed contacting anvils mounted for rotation in said housing with running clearance between said anvils and said housing, said anvils having flat circular working faces in fully confronting relationship defining a rock-crushing zone therebetween, one of said anvils having a face inclined relative to the axis of rotation to cause longitudinal movement of the other of said anvils, and spring means urging said anvils toward each other, whereby when rock becomes lodged between said anvil faces the contact between the faces will temporarily be broken and continued rotation of the anvils will cause a squeezing action to be applied to the rock resulting in a series of hammer-like blows as the rock crumples between the anvil faces.
